UNITED STATES PATENT OFFICE.

BENJAMIN E. MORSE, OF CANTON, MASSACHUSETTS.

CAN-OPENER.

No. 927,744.

Specification of Letters Patent.

Patented July 13, 1909.

Application filed November 20, 1908. Serial No. 463,522.

To all whom it may concern:

Be it known that I, BENJAMIN E. MORSE, a citizen of the United States, and resident of Canton, county of Norfolk, and State of Massachusetts, have made certain new and useful Inventions Relating to Can-Openers, of which the following is a specification, taken in connection with the accompanying drawing, forming part of the same.

10 This invention relates to can openers and relates especially to lever openers adapted to be pivotally mounted on the cover flange of tin cans or the like so as to engage the lip or other part of the can body and disengage the 15 cover therefrom.

In the accompanying drawings showing in a somewhat diagrammatic manner an illustrative embodiment of this invention and in which the same reference numeral refers to 20 similar parts in the several figures: Figure 1 is a side elevation of a can and attached opener, parts being broken away. Fig. 2 is an enlarged vertical section of the cover and attached opener. Fig. 3 is a similar section view before the parts have been assembled.

The opener lever may be pivotally mounted on either the cover or body member of the can in such position as to engage the operating member in opening the can. The 30 opener lever may, for example, be pivotally mounted on the cover flange so as to engage a coöperating portion when operated and force the cover from the can to the desired extent. The opener lever 7 may if desired be pivotally secured to the cover flange 3 by forming an integral pivot 12 on the lever adjacent its end which may be formed with a substantially flat shoulder adjacent the pivot 35 to make a more perfect joint with the cover flange in which a suitable hole 11 may be formed in any desired way to accommodate the pivot. A suitable handle such as 6 may be secured to the lever pivot in any desired 40 way as by forming a square aperture 10 in the reduced end 8 of the handle so as to accommodate the correspondingly shaped end 5 of the lever pivot. The pivot may then be forced through the hole 11 and its end inserted into the aperture 10 in the handle and secured therein as by riveting so as to form the desired operating connection between the lever and handle.

The lever is preferably formed with a suitable alining groove 9 extending around its op-

erating edges or faces so as to engage more definitely the lip 4 of the can body. When in operation the edge 14 of the opener lever passes between the cover flange and can lip and guides the latter into the alining groove. 60 It is thus apparent that as the handle 6 is swung downward from the position indicated in Fig. 1 the opener lever 7 engages the can lip 4 and further movement forces the cover 13 from the can 1 to the desired extent, the 65 lever being shown of such length in the illustrative embodiment that it is adapted to force the cover clear of the can on the side where the opener acts, although of course this is not necessary in all cases. By pivot- 70 ally securing the opener to the cover flange in this way a firm and substantially tight joint is made preventing any leakage of the contents from the can and the opener being attached to the cover is removed therewith 75 so as not to interfere in any way with the use of the can which is a decided advantage with cans or tin boxes adapted to contain stove polish and the like.

When the handle is swung up into horizontal position on either side of the pivot the cover may be replaced upon the can and the opener operated as described in removing the cover since the opener lever is of symmetrical form and has the same opening action 80 when forced downward in either direction. Furthermore, the opener when mounted on the cover flange as illustrated does not interfere with the application of a band label 2 to the can in the regular way. 90

Having described this invention in connection with an illustrative embodiment thereof, to the details of which disclosure the invention is not of course to be limited, what is claimed as new and what is desired to be secured by Letters Patent is set forth in the appended claims. 95

1. In can openers, an opener lever provided with opposed operating faces having an alining groove and edge extending along 100 the same and provided with a pivot having a square end projecting from said opener adjacent one end of the same, there being a flat shoulder around said pivot, a cover having a pivot aperture formed in its flange and a 105 handle having a reduced end formed with a square hole in which the end of said pivot is riveted to pivotally secure said handle and opener lever to said cover flange and to mount said lever within said cover in posi- 110

tion to engage the can lip in opening the can and to allow the application of a band label to said can.

2. In can openers, an opener lever provided with opposed operating faces having an alining groove extending along said faces and provided with a pivot having a square end, a cover having a pivot aperture formed in its flange and a handle formed with a square hole in which the end of said pivot is fastened to connect said pivoted handle with said opener lever and to mount said lever on the inner face of said cover flange in position to engage the can lip in opening the can.

10 3. In can openers, a double acting opener lever provided with an alining groove and with a projecting pivot, a cover having a pivot aperture formed therein and a handle secured to said pivot to pivotally connect

15 said handle with said opener lever and to mount said lever on the inner face of said cover in position to engage the can in opening the same when said opener lever is swung downward in either direction.

4. In can openers, a double acting opener lever provided with alining means and mounted within a can member, a connected handle and a pivot extending through said can member and connecting said lever and handle, said lever being thereby pivotally mounted on said member in position to engage the coöperating can member and open the can when said lever is swung out of either laterally inoperative positions.

BENJAMIN E. MORSE.
